TOY BALLOON

Filed May 16, 1922

FIG 1

FIG 2

FIG 3

FIG 4

Arthur P. Witten, Inventor

By F. E. Sharpen

Attorney

UNITED STATES PATENT OFFICE.

ARTHUR P. WITTEN, OF AKRON, OHIO.

TOY BALLOON.

Application filed May 16, 1922. Serial No. 561,473.

To all whom it may concern:

Be it known that I, ARTHUR P. WITTEN, a citizen of the United States, residing at Akron, in the county of Summit and State 5 of Ohio, have invented new and useful Improvements in Toy Balloons, of which the following is a specification.

This invention relates to toy balloons and has particular reference to an improved 10 closure means therefor.

It is an object of this invention to provide an inflatable, elastic balloon having associated therewith simple, efficient means whereby the same when inflated may be 15 closed and retained in an inflated condition.

Another object is to provide a toy balloon having permanently attached thereto a new and improved closure device of strong, durable construction which may be manufactured at a low price and which may be 20 quickly and conveniently operated to receive the neck of a toy balloon and hold the same in a closed position.

Further objects are to provide a closure 25 means which will be of light weight and which may be permanently secured to a toy balloon without injury thereto and which may be used without injuring or destroying the balloon.

The above objects are accomplished and additional ends are attained by the novel construction, combination and arrangement 30 of parts hereinafter described and illustrated in the accompanying drawings in which I have shown a preferred embodiment of the invention, it being understood that the invention is capable of various adaptations and that changes and modifications may be made or substitutions resorted to 35 which come within the scope of the claims hereunto appended.

In the drawings in which similar numerals of reference are used to designate similar or like parts as the same may appear 40 in any of the several views and in which:—

Figure 1 is a perspective view of a toy balloon constructed in accordance with this invention and showing the same inflated and closed by means of my improved closure device.

Figure 2 is a perspective view of my improved closure device.

Figure 3 is a side elevational view showing a toy balloon secured in an inflated condition by means of my improved device. 55

Figure 4 is a side elevational view of a toy balloon constructed in accordance with this invention and showing the manner of inflating same preparatory to closing the neck thereof. 60

Referring now to a detailed description of the invention with reference to the accompanying drawing, the numeral 5 is used to designate a rubber balloon which may be spherical as shown in the drawings or 65 of any desired shape. The balloon 5 is provided with an integral inflation stem or neck 6 which, as illustrated, is of ordinary construction and projects radially from the balloon. The numeral 7 denotes a closure 70 member which is preferably formed of wood or other light material.

In the particular adaptation of the invention shown, the member 7 is wedge-shaped having straight flat sides and a thick 75 end 7^a and a thin end 7^b. That portion of the area of one of the flat sides lying adjacent the thin end 7^b is coated with rubber cement or other adhesive and the member 7 is adhesively secured to the outer surface of the balloon at a point adjacent the stem 6 and with the thick end 7^a projecting toward the said stem. The member 7 is provided at a point adjacent the thick end 80 thereof with the notch 8 which projects into the said wedge from one edge thereof. The notch 8 is preferably formed with parallel side walls which are inclined toward the thick end 7. The notch 8 extends into the member 7 to a depth sufficient to receive and hold the neck 6 as hereinafter set forth. 85

In use, the balloon is inflated to the desired size, the neck 6 is then twisted to close the opening therein, whereupon the neck is stretched and forced into the notch 8 as 90 shown in Figures 1 and 2.

Having thus illustrated my invention and described the same in detail, what I claim as new and desire to secure by Letters-Patent is:—

1. In a toy balloon of the class described, to said balloon with the thick end thereof toward said stem and a notch in said member adjacent said thick end, said member adapted to receive and hold said neck. 10
an integral neck, a member adhesively secured to the exterior surface of said balloon at a point adjacent said neck, said member provided with a notch adapted to receive and hold said stem.
2. A rubber balloon having an integral neck and a wedge-shaped member secured

In testimony whereof I have hereunto set my hand.

ARTHUR P. WITTEN.
